UNITED STATES PATENT OFFICE

JOHN STUTIKA, OF WEST PULLMAN, ILLINOIS

VALVE-TESTING GAUGE

Application filed December 21, 1927. Serial No. 241,613.

This invention relates to valve testing devices, and more particularly to a device for testing the intake and exhaust valves of internal combustion engines.

5 As is well known, internal combustion engines cannot operate at their highest efficiency when the intake and exhaust valves do not seat perfectly throughout the circumferences of their engaging faces since there 10 is a loss of compression and explosive power, and damage always results to the exhaust valves when the latter fail to seat properly during the firing strokes of the engine. There is no visual means of determining 15 whether a valve is seating properly when it is in position in the engine due to the fact that the valve seat entirely surrounds the valve when the latter is in closed position, thus preventing an operator from obtaining a clear 20 view of the valve to determine whether it is firmly seated throughout its circumference.

An important object of the present invention is to provide a device by means of which it may be determined whether a valve face is 25 true and is adapted to seat properly when in closed position in the engine.

A further object is to provide a single valve testing device by means of which valves of varying diameters may be tested.

30 A further object is to provide a valve testing device which is adapted to be made of a single piece material and which is adapted to accommodate valves and valve stems of varying diameters.

35 A further object is to provide a device of the character referred to which is adapted for use in testing valves having their engaging faces arranged at angles to the axis of the valve stem or at right angles thereto.

40 A further object is to provide a device of the above mentioned character having a holder adapted to receive a valve stem, to support it in proper position, and to provide valve testing faces of material length and width 45 whereby the device is adapted to accommodate valves the engaging faces and stems of which are of varying diameters.

A further object is to provide a device of the character referred to which is adapted 50 to be held in one hand by the operator and

wherein the operator is permitted to hold the valve stem in position in the device with the thumb of the hand supporting the device, whereby he may employ the other hand for turning the valve stem to determine the accuracy with which the valve is adapted to seat.

Other objects and advantages of the invention will become apparent during the course of the following description.

In the drawings I have shown one embodiment of the invention. In this showing,

Figure 1 is a face view,

Figure 2 is a side elevation,

Figure 3 is a plan view, and

Figure 4 is a section on line 4-4 of Figure 1.

Referring to the drawings, the numeral 10 designates the device as a whole which may be cast, forged or stamped out of a single piece of material. The device includes a shank or body 11 which is substantially V-shaped in cross section as shown in Figure 4. At points spaced from its ends, the shank may be provided with guides or valve stem holding recesses 12 which are V-shaped as shown in Figure 4, and between the guides, and outwardly thereof, the inner face of the shank is recessed as at 13. It will be apparent that when a valve stem is arranged in the guides 12, it will contact only with these elements and thus be supported only at two points within the length of the shank. Thus a valve stem will be prevented from wobbling when in position if it should be slightly bent at a point between the guides.

Above the guides, the body is provided with a pair of outstanding angular arms 14, the inner faces 15 of which are of material length and width for a purpose to be described. The faces 15 are arranged at an angle to the axis of a valve stem arranged in the guides, corresponding to the angularity of the valve faces to be tested. It will be obvious that the faces 15 may be arranged at standard angles, such as 45° or 30° in accordance with the standard practice in manufacturing the engine valves.

The body of the device also is provided at its opposite end with lateral projections 16

having valve engaging lower faces 17 which are adapted to be used when the valve to be tested is provided with a valve seat engaging face arranged at right angles to the stem of the valve.

5 The operation of the device is as follows:

A valve stem is arranged in the guides 12 with the valve itself located between the engaging faces 15, when the valve to be tested 10 is of the poppet type having an angular or conical engaging face. The operator may grasp the shank 11 in his left hand and place the thumb of the same hand upon the valve stem between the guides 12 to hold the stem 15 in proper position. With one or both sides of the valve face engaging either or both of the faces 15, the operator may turn the lower end of the valve stem slowly with his right hand, at the same time observing 20 whether the valve face engages both of the faces 15. If these faces are engaged by both sides of the valve throughout a complete revolution thereof, it is obvious that the valve face is true, and that the valve is adapted 25 properly to function as an operating part of the engine. If, during any portion of the rotation of the valve, only one side thereof engages one of the faces 15, it is obvious that the valve is not true. Under the latter conditions, if the valve is only slightly bent or 30 distorted, it may be ground or turned to a true face, whereupon it will be ready for use. If the distortion is material, it will be advisable of course, to discard the valve and employ a new valve in its place. When it is desired to test a valve having a flat engaging face at right angles to the axis of the stem, it will be apparent that it is merely necessary to reverse the device to employ the 35 engaging faces 17. A different valve testing device obviously must be employed for valves having engaging faces of varying angularity. It will be apparent that the guides 12 are of material depth, and accordingly these 40 elements are adapted to receive valve stems of varying diameters. The position of a valve stem in the guides obviously will be determined by the diameter of the stem, stems of different sizes occupying different positions in the guides. It also will be apparent 45 that valves secured to stems of varying diameters will occupy different positions transversely with respect to the faces 15, and accordingly the latter are made of material 50 width in order to accommodate valves having stems of varying diameters. The valve faces 15 are of material length, and therefore, the device is readily adapted for the testing of valves having engaging faces of different 55 diameters. The device is extremely simple in construction and cheap to manufacture, and the valves are adapted to be quickly and accurately tested. Thus the use of bent or distorted valves in an internal combustion 60 engine readily may be avoided, together with 65

the disadvantages incident to the use of such valves. It is comparatively easy therefore, to maintain an engine at its highest operating efficiency so far as the operation of the valves is concerned.

70 It is to be understood that the form of the invention herewith shown and described is to be taken as a preferred example of the same and that various changes in the shape, size and arrangement of parts may be resorted to without departing from the spirit of the invention or the scope of the subjoined claim.

75 I claim:

A device of the character described comprising an elongated unitary body having a substantially V-shaped groove extending throughout the greater portion of its length, a pair of spaced substantially V-shaped relatively deep guides formed in portions of said body upstanding from said groove, said guides each having plane faces intersecting in a line common to both, and a pair of relatively long arms projecting from one end of said body and having faces of material width disposed diametrically opposite each other, 80 the line of intersection of the faces of said guides forming substantially a right angle with the line of intersection of the faces of said arms.

85 In testimony whereof I affix my signature.

JOHN STUTIKA.
